(57) **CLAIM**

The ornamental design for a multi-sided measuring spoon, as shown and described.

DESCRIPTION

FIG. 1 is a top front right perspective view showing a multi-sided measuring spoon showing my new design; FIG. 2 is a bottom front left perspective view thereof; FIG. 3 is a front elevation view thereof; FIG. 4 is a rear elevation view thereof; FIG. 5 is a right elevation view thereof; FIG. 6 is a left elevation view thereof; FIG. 7 is a top plan view thereof; and, FIG. 8 is a bottom plan view thereof.

The broken lines shown in the drawings depict environmental structure that forms no part of the claimed invention.
